CLAIM

The ornamental design for an ultrasonic scanner for inspecting pipes and pipe elbows, as shown and described.

DESCRIPTION

FIG. 1 is a first isometric view of an ultrasonic scanner for inspecting pipes and pipe elbows.

FIG. 2 is a second isometric view thereof.

FIG. 3 is a front view thereof.

FIG. 4 is a back view thereof.

FIG. 5 is a top view thereof.

FIG. 6 is a bottom view thereof.

FIG. 7 is a right side view thereof; and,

FIG. 8 is a left side view thereof.

The broken lines illustrate portions of the ultrasonic scanner for inspecting pipes and pipe elbows that form no part of the claimed design.
